PAUL N. MARTIN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTROMAGNETIC DEVICE

Application filed August 23, 1932. Serial No. 630,076.

My invention relates to electromagnetic devices of the type comprising an electromagnet and an armature coacting therewith and pivotally mounted on an axis, which is at a greater distance from one pole than from the other. One object of my invention is the construction of a magnet of this kind in such manner as to improve the torque characteristics of the device.

10 I will describe one form of device embodying my invention, and will then point out the novel features thereof in the claim.

In the accompanying drawing, Fig. 1 is a view showing in front elevation one form of electromagnetic device embodying my invention. Fig. 2 is a bottom view of the device shown in Fig. 1.

Similar reference characters refer to similar parts in each of the views.

20 Referring to the drawing, the reference character M designates an electromagnet comprising two parallel cores 2A and 2B connected at their upper ends by a backstrap 3. Core 2A is provided with a pole 6A, and core 2B is provided with a pole 6B. In accordance with my invention the area of the pole 6A is considerably less than the area of the pole 6B. Coacting with the magnet M is an armature C pivotally mounted on an axis 4, which axis is adjacent the outer edge of the smaller core 6A and in perpendicular to the general plane of the magnet M. The closed or energized position of the armature C is limited by a core pin 5 in the face of the pole 6B. In order to simplify the following explanation, I will refer to the air gap between the pole 6A and the armature C as the air gap A, and I will refer to the air gap between the pole 6B and the armature C as the air gap B.

Ordinarily, electromagnetic devices of the type to which this invention relates are constructed with the two poles of the same size, and when so constructed the curve plotted 45 between torque exerted on the armature and the amount of armature opening, for constant ampere turn energization, is very steep. That is to say, the torque is large for a small armature opening, but decreases very rapidly 50 as the armature opening increases. Since

this characteristic tends to make the energization value for pick up of the armature high and the energization value for release without contact pressure quite low, it is undesirable when the electromagnetic device is used as part of a track relay for a railway signal system. By constructing the device in the manner described, however, I have reduced the steepness of the torque curve and have therefore improved the characteristics of the device for use as a track relay.

The decrease in torque with increase of armature opening is caused mainly by the increase in reluctance of the air gaps between the armature and the poles and the consequent reduction in magnetic flux. The reluctance of the front air gap B increases more rapidly than that of the rear air gap A as the armature opening increases, because air gap B is at a greater radius than air gap A 55 from the pivotal point 4. This rapid increase in reluctance of air gap B causes the steep torque curve when the two air gaps are equal in area. By making the area of the front air gap B larger than that of air gap A, the reluctance of air gap B at small openings is decreased to a small part of the total reluctance of the two air gaps in series. Although the reluctance of gap B will still increase rapidly with increase in armature 60 opening, its effect on the total reluctance will be reduced. For example, I will assume that the two poles, and therefore the two air gaps, are of equal areas, and that the total reluctance of the two gaps in series, with the armature in closed position, is R, that the reluctance of the rear air gap A is $RA=1/2R$, and that the reluctance of the front air gap B is $RB=1/2R$. As the armature moves away from its closed position, RB increases 65 much more rapidly than RA, so that when RA has doubled and is therefore equal to $2 \times 1/2R=R$, RB may have increased three times as such and is thus equal to $3R$. The total reluctance will then be $R+3R=4R$.

Considering now the structure shown in the drawing, I will assume as before that the total reluctance of the two air gaps in series with the armature in its closed position is equal to R, but that the reluctance of the rear 70

gap A is $2/3R$ and that the reluctance of the front gap B is $1/3R$. When the armature has moved away from its closed position far enough to double RA so that $RA = 2 \times 2/3R = 4/3R$, and assuming again that RB increases three times as fast as RA, RB will then equal $3 \times 2 \times 1/3R = 2R$. The total reluctance will then be $4/3R + 2R$, which is equal to $3 1/3R$ instead of $4R$ as before. Since the flux varies inversely as the reluctance and the torque varies as the square of the flux, it is evident that as the armature opens the torque of a device constructed in accordance with my invention decreases much less rapidly than that of a device constructed in the usual manner.

Although I have herein shown and described only one form of electromagnetic device embodying my invention, it is understood that various changes and modifications may be made therein within the scope of the appended claim without departing from the spirit and scope of my invention.

Having thus described my invention, what I claim is:

An electromagnetic device comprising an electromagnet having two poles of different areas, and an armature coacting with said poles and pivotally mounted on an axis which is located adjacent the outer edge of the pole of smaller area.

In testimony whereof I affix my signature.
PAUL N. MARTIN.
